UNITED STATES PATENT OFFICE.

GLENN F. COUCH, OF ROCHESTER, NEW YORK.

SIDE FRAME AND STRUCTURAL MEMBER.

Application filed January 19, 1927. Serial No. 162,133.

This invention relates to structural members of special cross section and, more particularly, to side frames for railway car trucks, certain members of which are so designed.

5 The principal object of my invention, generally considered, is the provision of structural members of special cross section whereby they are adapted to be cast or otherwise formed with a minimum amount of internal 10 stress, such members being so designed that they are particularly adapted to form parts of side frames for railway car trucks.

An object of my invention is the provision 15 of a side frame in which the compression member and portions of the tension member are of a special U section involving the flanges of the U being joined to the web thereof by portions generally straight or only slightly curved so that the strength of the section is 20 increased and cooling strains are minimized.

Another object of my invention is the provision of a side frame in which certain members thereof are formed of special configuration involving a curved outer surface and 25 substantially flat inner surfaces thereby economizing material and minimizing the formation of cracks and other imperfections in the metal.

A further object of my invention is the provision 30 of a side frame in which certain portions of the members thereof are of a special shape which is almost semi-octangular in that the flanges thereof are joined to a web by portions extending at approximately forty-five 35 degrees to said flanges and web.

A still further object of my invention is the formation of certain structural parts of a side frame or other truss of special U section involving a web which decreases in thickness 40 from the center toward the edges thereof and flanges which have generally greater overall transverse dimensions adjacent the free edges thereof.

Other objects and advantages of the invention 45 relating to the particular arrangement and combination of the various parts will become apparent as the description proceeds.

Referring to the drawings illustrating my invention, the scope whereof is defined by the 50 appended claims:

Figure 1 is a half side elevation of a side frame for railway car trucks embodying the principles of my invention.

Figures 2 and 3 are transverse sectional views on the correspondingly numbered lines 55 of Figure 1.

Figure 4 is a sectional view corresponding to Figure 2 but showing a modification.

Figure 5 is a sectional view corresponding to Figure 2 but showing a further modification.

Referring to the drawings in detail, like parts being designated by like reference characters and first considering the embodiment of my invention illustrated in Figures 1, 2 and 65 3, there is shown a portion of a side frame 1 formed with a compression member 2, a tension member 3 and bolster guide columns 4, only one of which is shown, spacing intermediate portions of said members, leaving a 70 window opening 5 therebetween. The compression member 2 is connected to the tension member 3 at points near the end of the frame and said members are also connected to integral journal boxes 6 in the present embodiment although I do not wish to be limited to such construction as, instead of integral journal boxes, jaw-shaped portions may be provided for connecting with separable journal boxes. 75

In the present embodiment, the compression member 2 is of special U-shape in cross section with an upper web 7 and depending side flanges 8, said flanges 8 being joined to the web 7 by inclined portions 9 giving the 85 section somewhat the shape of half an octagon except that the inclined portions 9 need not be as long as the web 7 in order to provide a section equivalent to half an equilateral octagon. The free edges of the flanges 8 are 90 preferably flared downwardly and outwardly to provide beading as indicated at 10, said beading preferably extending at forty-five degrees to the flanges 8 or parallel to the inclined portions 9. 95

The tension member 3, and particularly the diagonal end portions 11 thereof, may be of a shape corresponding to that shown in Figure 2 except that the section is inverted. Those portions of the tension member, however, between the bolster guide columns 4, may be of normal box shape in section, as shown in Figure 3, except that the junction between the lower web 12 and side webs 13 thereof may correspond to that between the flanges 8 and the web 7, as indicated at 14 and the junction 100 105

between the side webs 13 and the upper web 15 may involve a flaring portion as indicated at 16.

The bolster guide columns 4 may correspond in cross section with Figure 2 except that the web 17 preferably joins with the side flanges 18 at ninety degree in accordance with usual practice rather than being formed with a supplemental portion at forty-five degrees 10 therebetween.

Referring now to the embodiment of my invention illustrated in Figure 4, a section is there disclosed very much like the section illustrated in Figure 2 except that the outer 15 surface of the web 7^a is convex or cylindrical rather than flat and the diagonal connecting portions 9^a between the flanges 8^a and the web 7^a involve filleted or curved portions 19 of greater radii than those of the first embodiment given an easier transition between the 20 diagonal portions 9^a and the adjacent web and flanges.

The free edges of the flanges 8^a may be provided with beading 19^a corresponding substantially to the beading of the first embodiment, except for filleted portions 20 between the outer surfaces of the flanges 8^a and said beading, thereby involving an effective thickening of the free edges of said flanges and 30 the avoidance of a relatively sharp angle between said flanges and beading. Although only the section of the compression member is illustrated for this embodiment, it will be obvious that the tension member and the bolster guide columns may be of corresponding section modified as indicated in connection with the first embodiment.

Referring now to the modification of my invention illustrated in Figure 5, a special U 40 section for the compression member is there disclosed involving an upper web 7^b and depending side flanges 8^b, the lower ends of said flanges being flared outwardly or increased in width to form beading 10^b. The 45 inner surfaces of the web and flanges are substantially flat as shown except for the junctions therebetween which involve filleted portions 9^b of relatively large radii approximating the inclined connecting portions 9^a of the embodiment illustrated in Figure 4. The 50 outer surfaces of the web and flanges, however, are curved, that of the web 7^b being convex to cause an increased thickness at the center thereof and that of the flanges 8^b being concave, for the major portion thereof, to provide an increased thickness at the free edges thereof and form the beading or ribs 10^b.

Although only the compression member is 60 illustrated in section for this modification yet it is obvious that the tension member and bolster guide columns may have a corresponding section modified to correspond with the function of said members as described in

connection with the first embodiment, that is, for example, the transverse section of the bolster guide columns and particularly the bolster guiding portions thereof corresponds substantially with the compression member except that the inner or bolster guiding surfaces are preferably flat instead of convex.

From the foregoing description of the preferred embodiments of my invention taken in connection with the accompanying drawings, it will be seen that I have provided an improvement over the ordinary U section not only for portions of side frames but also for structural members of any desired character which, not only results in greater strength for a given weight of metal, but obviates the formation of imperfections upon cooling of the metal after the same has been cast.

Having now described my invention, I claim:

1. A cast side frame comprising a member generally U-shaped in cross section, the web and flanges of said U being joined by inclined portions whereby the section thereof substantially corresponds with a portion of an octagon. 85

2. A cast side frame comprising a member thereof generally U-shaped in cross section and involving a web and generally Z-shaped flanges extending therefrom. 90

3. A side frame comprising a member substantially U-shaped in cross section, the web of said U being flat on its interior surface and cylindrical on its exterior surface. 95

4. A side frame comprising a member substantially U-shaped in cross section, the interior surfaces of the web and flanges of which are substantially flat and the exterior surfaces of which are curved. 100

5. A side frame comprising a member generally U-shaped in cross section, the web of which is relatively thick adjacent the longitudinal center line thereof and decreases in thickness toward the junctions with the flanges thereof, said flanges increasing in thickness toward their free edges. 105

6. A structural member generally U-shaped in cross section with the junctions between the web and flanges thereof being inclined to approximate a portion of an octagon and the free ends of the flanges flared diagonally. 110

7. A structural member substantially U-shaped in cross section, the web of said U being flat on its interior surface and cylindrical in its exterior surface. 115

8. A structural member substantially U-shaped in cross section, the interior surfaces of which are substantially flat and the exterior surfaces of which are curved. 120

9. A structural member generally U-shaped in cross section, the web of which is relatively thick adjacent the longitudinal center line thereof and gradually decreases in thickness toward the junctions with the flanges thereof, 125

said flanges increasing in thickness toward their free edges.

10. A structural member generally U-shaped in cross section, the web of which is relatively thick adjacent the longitudinal center line thereof and decreases in thickness toward the junctions with the flanges thereof, said flanges having diagonally disposed portions joining said web.

10 11. A structural member generally U-shaped in cross section, the flanges of which increase in thickness toward their free edges, and the free ends of which are angularly dis-

posed with respect to intermediate portions thereof.

15

12. A structural member generally U-shaped in cross section and comprising a web and flanges extending therefrom, said flanges being generally Z-shaped in cross section with the upper and lower portions of the Z disposed at substantially forty-five degrees with respect to the intermediate portion thereof.

20

In testimony whereof I affix my signature.

GLENN F. COUCH.
